UNITED STATES PATENT OFFICE.

JOHN B. MITULSKI, OF DETROIT, MICHIGAN.

AUTOMATIC WATER FEED FOR HOT-AIR-FURNACE HUMIDORS.

Application filed March 27, 1926. Serial No. 97,929.

This invention relates to humidors for hot-air furnaces and has for its primary object to provide means for automatically maintaining the humidor supplied with water for overcoming the requirement of manually replenishing the humidor with water when necessary.

A further object of the invention resides in the provision of means whereby the water will be automatically fed into the humidor from the usual water heating pipe within the furnace, and this without requiring any unusual alteration of the furnace and without requiring great expenditure in the installation of the water feed mechanism.

Other objects of the invention will become apparent as the nature of the invention is better understood, the same comprising the novel form, combination, and arrangement of parts hereinafter more fully described, shown in the accompanying drawing and claimed.

In the drawing wherein like reference characters indicate corresponding parts throughout the several views:

Figure 1 is a fragmentary view in side elevation partly broken away and partly in cross section of a conventional hot air furnace wherein the humidor is equipped with my novel automatic water feed.

Figure 2 is an enlarged top plan of the float controlled valve actuating member of the water feed.

Figure 3 is an enlarged section taken through the discharge end of the water pipe that is arranged within the humidor for more clearly disclosing the valve mechanism of the present device, and

Figure 4 is a detail of the supporting element for the float controlled valve operating member.

Now having particular reference to the drawing, 5 indicates a conventional hot air furnace at one side of which is a water tank 6, into the lower end of which leads a hot water pipe 7 that is in communication with a water heating coil 8 located within the furnace, said coil being in turn in communication with the source of water supply, and which coil is usually located within the furnace above the fire grate thereof. As is usual, the humidor pan 9 is arranged within the rear side of the furnace, and is adapted to contain a supply of water in order that

the furnace will discharge moistened air. In carrying out my invention, the connection between the tank pipe 7 and coil 8 has attached thereto and in communication therewith a branch pipe 10, the discharge end of which terminates above the humidor pan 9 at one side thereof, said end being equipped with an elbow 11 that turns downwardly in the direction of the pan as clearly shown in Figure 1. The lower end of said elbow 11 is internally threaded, Figure 3, and is adapted to receive a threaded plug 12 formed with a central bore 13, said plug being formed adjacent its lower end with an annular shoulder 14 for a purpose to be hereinafter more fully described.

Arranged over the plug 12 above the shoulder 14 is an annulus 15 that is adapted to be secured in place between the shoulder at the lower edge of the elbow by turning the plug inwardly of the elbow. For preventing leakage between the elbow and said plug, gaskets 16 are disposed upon the plate and upon the elbow shoulder, which gaskets will be compressed when the plug is turned inwardly of the elbow.

Formed upon diametrically opposite points of the annulus 15 are downwardly extending inclined arms 16—16 between which the yoked inner end 17 of a valve rod 18 is pivoted by reason of a cross pin 19. The forward end of said rod is equipped with a float 20 operable by the fluid within the humidor pan 9.

Loosely arranged in the bore 13 of the elbow plug 12 is a valve stem 21 that is pivoted at its lower end between the arms of the yoke 17 of said float rod 18 and carries at its upper end a disc-like valve 22 that will when the float 20 is moved upwardly under the action of the water within the humidor pan close the bore of the plug for preventing the passage of the water therethrough. On the other hand when the float lowers, the valve will be raised from the plug to permit an additional supply of water to enter said humidor pan.

It will thus be seen that I have provided a highly novel, simple, but yet extremely efficient means of supplying water in an automatic manner to the humidor pans of hot air furnaces, and even though I have herein shown and described the invention as describing certain detailed elements of con-

struction, it is nevertheless to be understood that departures may be had from the showing without affecting the spirit and scope of the appended claim.

Having thus described the invention, what I claim as new and desire to secure by Letters Patent is:—

A furnace attachment to be used with a humidor pan comprising a pipe adapted to lead into said pan, an elbow arranged upon the discharge end of the pipe and adapted to extend downwardly into the pan, a plug arranged in the free end of the elbow and being

formed with a bore therethrough, a circular shoulder formed upon the lower end of the plug, an annulus arranged about the plug and adapted to be secured between the elbow and the shoulder, arms extending downwardly from the annulus, a float-controlled valve actuating rod pivoted adjacent one end between said arms, a valve having a shank extending through the bore of the plug and attached to the end of the said rod.

In testimony whereof I affix my signature.

JOHN B. MITULSKI.
